ISAAC GOLDBERG INVENTOR

BY
Wm. Finstan
ATTORNEY

UNITED STATES PATENT OFFICE.

ISAAC GOLDBERG, OF NEW YORK, N. Y.

UMBRELLA AND THE LIKE ARTICLE.

Application filed February 8, 1926. Serial No. 86,875.

This invention relates to umbrellas. More particularly it is directed to an umbrella having electric lighting means incorporated in its frame structure.

5 One object of the invention is to provide an improved electric lighting means which is readily adapted to be incorporated in an umbrella using standard parts in the construction thereof.

10 Other objects of this invention will in part be obvious and in part hereinafter pointed out.

Certain features herein shown and described are shown, described and claimed 15 in my co-pending application Serial No. 86,874 filed February 8th, 1926, and accordingly are not claimed herein.

With the above exception the invention accordingly consists in the features of construction, combinations of elements and arrangement of parts which will be exemplified in the construction hereinafter described, and of which the scope of application will be indicated in the following claims.

25 In the accompanying drawing, in which is shown one of the various possible illustrative embodiments of this invention,

Fig. 1 is a front elevational view of an improved umbrella having an electric lighting means embodying the invention partly broken away to show the construction;

30 Figs. 2 and 3 are cross-sectional views of the tip and handle portions of the umbrella respectively; and

35 Fig. 4 is a modified form of umbrella tip construction embodying the invention; and

Fig. 5 is a sectional view showing the parts of the lighting means in the umbrella tip removed therefrom and separated.

40 Referring in detail to the drawing, U denotes an umbrella constructed to embody the invention. Said umbrella may comprise a handle H mounted on one end of a tubular steel rod R, the other end of which supports 45 a collapsible frame F. A cover C extends over and is secured to ribs 10 of said frame F and stretchers 10^c thereof are pivoted between mid-portion 10^a of said ribs and a runner 13 slidably mounted to ride along rod

50 R, the inner ends of said ribs being pivoted so that the ribs extend radially about a notched fitting 11 mounted adjacent the top 12 of said rod. Said umbrella handle, rod, frame and cover may be of any suitable make

and assembled in any manner well understood in the art.

An electric lighting means is incorporated in the umbrella structure and is seen to comprise a suitable electric power source such as a standard type of cylindrical dry cell battery 20 inserted in a compartment 13 in the handle H, a switch 21 conveniently positioned adjacent the handle, and a conductor wire 22 passing through the tubular rod R for connecting said battery to a plurality of 60 lights 30 and 31 mounted in the umbrella tip 12 to illuminate the umbrella on the exterior and inner side of the cover C, as shown in Figs. 1 and 2.

The body portion of the handle H preferably comprises a sheet metal casing 14, the free end 14^a thereof being provided with a suitable closure for the compartment 13 such as a demountable knob 15. The latter has a coil spring 15^a for electrically connecting 70 the outer terminal 20^a of the battery 20 to the handle casing 14 in the well understood manner. The other end 14^b of said casing may have a plug 16 made of any suitable insulating material such as wood, fibre, or the like, secured therein into which the end 17 75 of the rod R extends and is firmly anchored.

The switch 21 is here seen to comprise a metallic disc 21^a which is loosely mounted for limited movement along the rod R and 80 is normally spaced over the handle H so as not to contact with the casing 14, as shown in the full lines in Fig. 3. Said disc is conveniently positioned to be tilted by the finger 85 of the user for electrically interconnecting the rod R with the casing 14, whereby the circuit from the battery to the lights is completed, as will hereinafter appear.

The conductor wire 22 is anchored at its lower end 22^a to a fixed terminal contact 95 23 mounted on the plug 16 and is insulated from the rod R, said contact 23 being connected to the central terminal 20^b of the battery 20.

The upper end 22^b of said conductor wire 100 is carried up to the umbrella tip 12 where it connects with the lights 30 and 31.

As will be seen from Figs. 1 and 2, the umbrella tip 12 forms a housing for the lights 30 and 31 of the electric lighting means and may be made of transparent material such as celluloid, bakelite, or the like substance. Said housing 12 is preferably 105

constructed of two parts, a lower and upper part 12^a and 12^b respectively, within which a chamber 12^c is provided for receiving said lights.

5 The lower part 12^a is fixedly fitted into a mounting piece 33 which is made to receive, and is anchored to the upper end 18 of the rod R, said part 12^a serving to rigidly support the notched fitting 11 of the frame F.

10 The upper part 12^b which forms the tip end of the umbrella is demountably secured in position to abut the lower part 12^a by providing a quickly detachable connecting means of any suitable construction, as, for 15 example, an internally threaded projecting portion 11^a on said notched fitting 11 into which is screwed the exteriorly threaded inner end portion 12^d of said part 12^b.

20 Removably mounted to extend downwardly from the top end of the housing part 12^b into the chamber 12^c, there is a lamp socket 30^a and lamp 30^b which form the light 30. A similar lamp socket 31^a and lamp 31^b forming the light 31 is mounted 25 to extend upwardly into the upper end of the chamber portion 12^c in the part 12^b.

20 To connect the lamps 30^b and 31^b to the power supply through the conductor wire 22, a detachable tapping means of suitable 30 construction may be provided such as a disc 40 having contacts 40^a and 40^b thereon. Said disc 40 is clamped between the sockets 30^a and 31^a so that the center contact terminals 30^c and 31^c and the shell contact terminals 35 30^d and 31^d from the lamps 30^b and 31^b, respectively, engage with said disc contacts 40^a and 40^b, respectively, as shown in Figs. 2 and 5. The disc contact 40^a may serve 40 to terminate the upper end of the conductor wire 22, the upper portion of which extends through a passage 12^e provided in the wall of the chamber 12 in the housing part 12^a alongside the socket 30^a. The other disc contact 40^b may be grounded to the frame 45 F and rod R in any suitable manner. As here shown there is a spring blade 41 secured to extend from said contact 40^b which is bent to fit into a pocket 12^f provided between housing part 12^a and the notched fitting 11, the blade contacting with said fitting and the latter electrically connecting at 11^b with the rod R through the mounting piece 33.

50 The control of the lighting means will now be apparent. On pressing the switch disc 21^a, it is tilted, closing the circuit from the battery terminal 20^a to the rod R through the handle casing 14 and knob 15. The current will then flow from the battery 55 terminal 20^b through conductor wires 22, thence to the lamps 30 and 31 and then to the rod R through the blade 41 and fitting 33 grounded to said rod, the circuit being completed through the switch 21 to the battery terminal 20^a. The lights 30 and 31 instead

of being connected in parallel circuit as shown may be joined in series in the well understood manner, in which case the light 30 will serve as a signal to indicate whether or not the light 31 is functioning.

70 It is apparent from the drawing that the lamp 30^b and 31^b may easily be replaced by simply dismounting the housing part 12^b and removing the lights 31 and 32 from the chamber 12^c, a slack portion 22^b being provided adjacent the upper end of the wire 22 in the chamber 12 to permit the removal of said lights.

75 In Fig. 4 is shewn a modified umbrella tip construction embodying the invention. 80 Here the tip or housing 112 is constructed of metal, the lower housing part 112^a being made integral with the notched member 111, and the upper housing part 112^b being screwed into the threaded projecting portion 111^e of said member 111. The housing 112 is provided with openings 112^c having transparent windows 120 made of celluloid or other so called "non-breakable" material through which the light from the lamps 30^b 85 and 31^b pass.

90 It will thus be seen that there is provided a device in which the several objects of this invention are achieved and which is well adapted to meet the conditions of practical 95 use.

95 As various possible embodiments might be made of the above invention, and as various changes might be made in the embodiment above set forth, it is to be understood that 100 all matter herein set forth or shown in the accompanying drawing is to be interpreted as illustrative and not in a limiting sense.

Having thus described my invention, I claim as new and desire to secure by Letters Patent:—

1. The combination with an umbrella having a rod, a tip on one end of the rod, and a collapsible frame mounted on said tip, of a light positioned to extend inwardly in said tip adapted to illuminate the inner side of the umbrella.

2. The combination with an umbrella having a rod, a tip on one end of the rod, and a collapsible frame mounted on said tip, of a plurality of lights positioned within said tip adapted to illuminate both interior and exterior sides of the umbrella.

3. In a device of the character described, an umbrella having a rod, a hollow handle 120 on one end of said rod, a tip on the other end of said rod and lighting means comprising a power source encased in said handle, a conductor wire extending through said rod, lamps connected to said power source 125 through said wire mounted entirely within said tip, and a switch mounted between the handle and rod for controlling said lighting means, said rod and handle being normally insulated from each other and adapted to 130

be electrically interconnected on operating of said switch.

4. In combination, a rod carrying an umbrella top, a tip on one end of said rod, and 5 lighting means for illuminating opposite sides of said top mounted in said tip.

5. In combination, a metallic rod carrying an umbrella top, a tip on one end of said rod, and lighting means for illuminating opposite sides of said top mounted in said tip, 10 a metallic handle for, and insulated from, said rod, and means associated with said rod and handle, for completing an electric circuit between said rod and handle.

6. In a device of the character described, 15 in combination with a metal tubular umbrella handle adapted to receive a battery and a metal tubular umbrella rod supporting a light, an insulating piece separating said handle and rod, and a metal piece member 20 encompassing said rod and capable of being slightly rocked on said insulating piece, the end of the handle being situated so that upon rocking the encompassing piece an electric circuit will be completed between said rod 25 and handle.

In testimony whereof I affix my signature.
ISAAC GOLDBERG.
